CLAIM

I claim the ornamental design for an extruded metal section, as shown and described.

DESCRIPTION

FIG. 1 is a front perspective view of an extruded metal section showing my new, original and ornamental design; and,

FIG. 2 is an end view of the extruded metal section illustrated in FIG. 1.

The extruded metal section is broken away to indicate indefinite length.

The surface(s) or portion(s) of the article not shown in the drawing or described in the specification form(s) no part of the claimed design.
